SELF-SHARPENING SAFETY RAZOR

Joseph Albert Guimond, Montreal, Quebec,
Canada

Application November 18, 1937, Serial No. 175,332

1 Claim. (Cl. 30—36)

This invention relates to safety razors and more particularly to a means whereby the blade, while held in the razor, can be sharpened quickly, the sharpening element being a part of the 5 razor and located normally where it will not interfere with the shaving operation.

A further object is to provide a structure of this character which is simple and compact in construction, formed of few parts, will not readily get out of order, and can be easily actuated for 10 the purpose of sharpening the blade.

With the foregoing and other objects in view which will appear as the description proceeds, the invention consists of certain novel details of 15 construction and combinations of parts hereinafter more fully described and pointed out in the claim, it being understood that changes may be made in the construction and arrangement of parts without departing from the spirit of the 20 invention as claimed.

In the accompanying drawing the preferred forms of the invention have been shown.

In said drawing

Figure 1 is a front elevation of the razor.

Figure 2 is a section on line 2—2, Figure 1, the sharpening element being shown in engagement with the cutting edge of the blade.

Figure 3 is a view similar to Figure 2 showing the sharpening element retracted and the cutting 30 edge of the blade in operative position.

Figure 4 is a perspective view of the sharpening element.

Figure 5 is a section through a portion of the handle of a modified form of razor showing the 35 same utilized as a housing for a shaving brush.

Referring to the figures by characters of reference 1 designates a handle which can be of any desired shape and size. In the structure shown in Figures 1, 2 and 3 this handle is solid but it is to be understood that, if desired, the handle 40 can be made hollow as shown at 2 in Figure 5, the recess affixed in the handle opening through one end thereof but being normally closed by a removable cap 4. In this handle is slidably 45 mounted the base 5 of a shaving brush 6, there being a knob 7 connected to the base and slideable along a slot 8 in the handle. Thus after the cap 4 has been removed, knob 7 can be shifted in one direction to bring the brush in position where it can be used for shaving purposes. While 50 the brush is thus extended it can be secured in any manner desired. For example knob 7 can be located at one end of an elongated screw 9 extending through base 5. Thus when the knob 55 is rotated it will bind upon the handle 2 and

hold the base in any position to which it might be moved.

The handle in either form of the device is formed with a slotted head 10 having a flat end plate 11 preferably made integral therewith and formed along one edge with spaced guard teeth or fingers 12 such as commonly used in safety razor constructions. This plate 11 has a slot 13 opening into the slot 14 in head 10, and slidably mounted on plate 11 is a flat sharpening element 15 which can be a thin metal plate or a plate of glass or any other suitable sharpening material from which depends an ear 15' adapted to slide within slot 13. This ear has an elongated slot 16 which receives a pin 17 extending through 20 an operating wheel 18. The wheel is mounted for rotation in slot 14 on a cross pin 19. It is to be understood that ear 15' can be forked, as shown in Figure 1 so as to straddle the wheel 18 and thus be held against lateral movement relative 20 thereto.

The wheel is formed in its periphery with notches 20 and these notched portions of the wheel project outwardly in opposite directions respectively from the slot 14 so that a finger of 25 the hand of the user can be employed to move the wheel back and forth about its axis of rotation, thereby transmitting motion through pin 17 and ear 15' to the sharpening element 15 which thus will be reciprocated upon the outer 30 surface of the plate 11.

Plate 11 is provided at one edge with a flange 21 which can carry an integral supporting ledge 22 shaped to support the enlarged or thickened back portion A of a razor blade B. One or more 35 spring clips 23 can be suitably joined to the flange 21, these clips being so shaped and proportioned as to overlie and exert a downward pressure upon the back A of blade B. Thus the cutting edge C of the blade will be held normally 40 pressed against the guard fingers 12 at a point where it will operate efficiently to shave a person. Under these conditions the sharpening element 15 will be located between the flange 21 and the cutting edge portion of the blade, as 45 shown in Figure 3.

While the parts are located as in Figure 3 the razor can be used in the same manner as an ordinary safety razor. However should it be desired to sharpen the blade B, all that is necessary 50 is for the user to rotate wheel 18 in one direction so as to thrust the sharpening element 15 forwardly between the cutting edge of blade B and the guard fingers 12. This has been shown in Figure 2. While the sharpening element is thus 55

located the wheel can be rotated back and forth, thereby causing said element to reciprocate and as it is constantly contacted by the cutting edge portion C of the blade, said edge will be quickly sharpened. After the cutting edge has been treated in this manner, the sharpening element 15 is shifted back to the position shown in Figure 3 and the razor can then be used as before.

The razor blade can be placed in or removed 10 from position by sliding it longitudinally between the ledge 22 and the clip or clips 23.

What is claimed is:

A safety razor including a handle, a longitudinally slotted head thereon, an end plate integral with the head and having a slot, guard fingers integral with and extending from one edge of the plate, said plate having a flat supporting surface, a pivot device fixedly mounted in the head and extending across the slot therein, a 20 wheel mounted for back and forth rotation on said pivot device within the slot in the head and extending into close proximity to and lying in the same plane with the slot in the plate, said

wheel having opposed portions extending outwardly from the slots for engagement by a finger of the hand grasping the handle for actuation thereby, a flat sharpening element slidably mounted on the plate and normally positioned back from but above the plane of the guard fingers, a blade-supporting ledge integral with the plate, yielding means cooperating with said ledge for gripping a razor blade and holding the sharpened edge of said blade normally in contact with the plate close to the guard fingers and in the path of the sharpening element, and means extending from the sharpening element and mounted for right line movement in the slot in the plate for actuation by the wheel when 15 rotated back and forth, said means and the wheel cooperating to reciprocate said sharpening element between the cutting edge of the held blade and the guard fingers and to withdraw said element from engagement with the cutting edge 20 into position between the slotted plate and the held blade.

JOSEPH ALBERT GUIMOND.
